INTERLOCKING ANVIL AND SWAGE BLOCK.

1,037,209.

Specification of Letters Patent.

Patented Sept. 3, 1912.

Application filed December 12, 1911. Serial No. 665,358.

To all whom it may concern:

Be it known that we, JAMES WESLEY COYLE and DANIEL E. LYNCH, citizens of the United States, residing at Carterville 5 and Webb City, respectively, in the county of Jasper and State of Missouri, have invented certain new and useful Improvements in Interlocking Anvil and Swage Blocks; and we do hereby declare the following to be a full, clear, and exact description of the invention, such as will enable others skilled in the art to which it appertains to make and use the same.

This invention relates to drill sharpening machines and more particularly to interlocking anvil and swage blocks therefor.

An object of the invention is to provide interlocking anvil and swage blocks.

Another object is to provide an anvil 20 block with an interrupted dove-tailed groove in its upper face to receive a correspondingly formed rib carried upon the under face of a swage block, and a wedge key for locking said blocks together.

Another object is to provide interlocking anvil and swage blocks of the above stated character which are adapted for employment upon certain types of drill sharpening 25 machines.

Another object is to generally improve the construction of this type of anvil and swage blocks.

Other objects and advantages will be hereinafter set forth and pointed out in the 35 specification and claims.

In the accompanying drawings which are made a part of this application, Figure 1, is a perspective view of the blocks in interlocked engagement with one another, also 40 showing the drill in one position upon the swage block. Fig. 2, is a perspective view of the anvil block alone, showing the interrupted dove-tailed groove in the upper face thereof. Fig. 3, is a vertical longitudinal 45 section through the blocks and tool, taken on the line 3—3 of Fig. 4, and, Fig. 4, is a vertical cross sectional view, taken on the line 4—4, Fig. 3.

Referring more particularly to the drawings in which similar reference numerals 50 designate corresponding parts throughout the several views, 1 represents the anvil block which preferably has its upper side edges 2 beveled. The side edges of the block 55 are provided with suitable grooves 3 to re-

ceive track rails (not shown), between the side plates of the framework of a drill sharpening machine. The front and rear edges of the anvil block may also be provided with grooves 4 similar to the grooves 60 3 and the block 1 may be mounted in any preferred manner between the side plates of the machine framework and may be adjustably secured, as desired.

The block 1 is divided in its upper face 65 with the interlocking dove-tailed groove 5 extending in a longitudinal direction. The dove-tail groove 5 is formed by the oppositely beveled walls 6 and 7, the wall 7 extending the full length of the block, while 70 the wall 6 is stopped short of the rear end of the block by means of the stop 8 at the rear end of the groove 5, one edge 9 of said stop facing the wall 7 and being positioned a slight distance from the latter and beveled in the same direction as the wall 6 and 75 at a degree corresponding to that at which the wall 7 is beveled. It will be understood that the wall 6 may be beveled at an angle corresponding to that of the wall 7 or at 80 a different angle as desired. The wall 10 of the stop 8, connecting the wall 9 of said stop and the wall 6 of the groove 5, is vertical and at right angles to said walls 9 and 6. The wall 10 forms the front wall of the 85 stop and its purpose will be later fully stated.

The swage block 11 is adapted to rest upon the upper face of the anvil block 1 and carries upon its under face the dove-tailed longitudinally extending rib 12 which is adapted 90 for engagement within the groove 5 in the upper face of the anvil block 1. The rib 12 stops short of the rear end of the swage block 11 and the rear end 13 of said rib is 95 vertical and adapted for engagement against the vertical front wall 10 of the stop 8 to stop or limit the rearward movement of the rib 12 within the groove 5. The opposite edges 14 and 15 of the rib 12 are beveled to correspond with the beveled walls 6 and 7, respectively, of the groove 5 and the edge 14 of said rib 12 is adapted for engagement against the wall 6. Owing to the fact, however, that the rib 12 is narrower 105 than the groove 5, the opposite edge 15 of said rib is spaced from the wall 7 and substantially in alignment with the wall 9 of the stop 8 when the edge 14 of the rib 12 is in engagement with the wall 6. This leaves 110

a space between the wall 7 of the groove 5 and the wall 9 of the stop 8, and between the wall 15 of the rib 12 and the wall 7. A wedge locking key 16 is then forced between 5 the walls 7 and 15 to tighten the swage block 11 upon the anvil block 1 and prevent disengagement of the rib 12 from the groove 5. It will be noted that the front end of the 10 swage block 11 projects slightly beyond the front edge of the anvil block 1 and the lower corner 17, adjacent the side edge 14 of the rib 12, engages against the front face of the anvil block 1, adjacent the wall 6 of said block when the swage block is in position 15 upon the anvil block 1 and the rear wall 13 of the rib 12 is engaged against the wall 10 of the stop 8. Thus it will be seen that a double stop is provided for limiting the rearward movement of the rib 12 within the 20 groove 5.

The form of the upper face of the swage block 11 may be varied as desired, but we prefer to bevel the forward portion 18 thereof and provide the same with a rearwardly 25 extending channel 19 of semi-circular form in cross section to receive one edge of a drill or other tool 20 for certain swaging operations. Upon the rear portion of the block 11 we provide the parallel spaced tool 30 supporting members 21 adapted to support and hold the shank 22 of the tool 20 therebetween. The forward ends of the members 21 are cut under, as shown at 23, to cause the formation of the rounded shoulders 24 of 35 the tool 20 upon the proper application of strokes upon the tool by the swaging or pounding hammer (not shown).

It will be seen by referring to Fig. 1, just 40 how the tool supporting members 21 serve to hold the tool 20 in position upon the swage block 11 and also the manner in which the cut under ends 23 of said members serve to produce the shoulders 24 of the tool 20.

It will be evident that the upper face of 45 the swage block 11 may be varied if desired or that a number of such blocks may be employed and each adapted to be secured in position upon the anvil block 1, as described.

When it is desired to round the opposite edges of the tool 20, the same is moved forward and placed at right angles to the position shown in Fig. 1, with one of the side edges 25 resting within the channel 19. The hammer may then be directed upon the opposite edge 25 to perform this operation. Thus it will be seen that we have provided an improved form of interlocking anvil and swage blocks and that the wedge key 16 may be readily withdrawn when it is desired to remove the swage block to replace the same with a different block or for any purpose desired.

What we claim is:

1. A device of the class described comprising an anvil block having an interrupted dovetail groove in its upper face extending from one edge of said block to the opposite edge thereof, said groove being interrupted at one end by a stop member positioned in said groove, a swage block having a dovetailed rib upon its under face, said rib stopping short at one end of the swage block, the rib being adapted for engagement with the interrupted groove of the anvil block, the end of the rib being adapted for 70 engagement against the stop member, and a key for locking the rib in the groove.

2. The combination with an anvil block having a groove across its upper face and a stop member positioned in one side of the groove and at one end thereof; of a swage block having a rib upon its under face for engagement within the groove and against the stop member, and locking means for engagement in the groove to one side of the rib and the stop member and against the same for locking the parts together.

In testimony whereof we have signed our names to this specification in the presence of two subscribing witnesses.

JAMES WESLEY COYLE.
DANIEL EMMETT LYNCH.
